SLINGSHOT

Julian B. Bell, Los Angeles, Calif.

Application June 6, 1951, Serial No. 15,440

Term of patent 14 years

(Cl. D34—15)

To all whom it may concern:

Be it known that I, Julian B. Bell, a citizen of the United States, residing at 3735 Collis Avenue, Los Angeles, in the county of Los Angeles and State of California, have invented a new, original, and ornamental Design for Slingshots, of which the following is a specification, reference being had to the accompanying drawing, forming part thereof.

Figure 1 is a front perspective view of a slingshot embodying my new design;

Figure 2 is a view in rear elevation of the slingshot; and

Figure 3 is a vertical section taken at the center of this slingshot on line 3—3 of Fig. 1.

The dominant features of my new design are shown in solid lines in the drawing. The dotted line showing of the pouch and elastic member have been omitted from Figs. 2 and 3 for convenience of illustration.

I claim:

The ornamental design for a slingshot, as shown and described.

JULIAN B. BELL.
